UNITED STATES PATENT OFFICE.

JAMES F. HOLLIS, OF PITTSBURG, PENNSYLVANIA.

RAIL-JOINT.

SPECIFICATION forming part of Letters Patent No. 724,867, dated April 7, 1903.

Application filed January 28, 1903. Serial No. 140,843. (No model.)

To all whom it may concern:

Be it known that I, JAMES F. HOLLIS, a citizen of the United States of America, residing at Pittsburgh, in the county of Allegheny and 5 State of Pennsylvania, have invented certain new and useful Improvements in Rail-Joints, of which the following is a specification, reference being had therein to the accompanying drawings.

10 This invention relates to certain new and useful improvements in rail-joints, the primary object of the invention being to construct a rail-joint whereby to effectually join the rails together without the aid of the bolts 15 passing through the webs of said rails and the nuts for holding said bolts in position.

A further object of the invention is to provide a rail-joint of this type with a stationary and a removable fish-plate whereby the rails 20 may be readily placed in position and the removable plate may be readily removed, whereby to permit the removal of the rails for replacing or other cause.

Briefly described, the invention comprises 25 a chair embodying a saddle-plate having one of the fish-plates formed integral therewith. This saddle-plate is provided with supporting-ledge, upon which the rails rest, the base of the rails on one side projecting over beyond 30 the ledge. This projecting portion of the rail-base is received in the groove formed in the base of the movable fish-plate, this movable fish-plate having a supporting-ledge to receive the projecting portion of the said rail-base. 35 The base-plate of the movable fish-plate is provided with an inclined or beveled wall which engages with the inclined or beveled wall formed on the inner edge of the strip or ridge formed integral with the saddle-plate. The saddle-plate is provided near 40 each end with apertures to receive securing-spikes, and apertures are also provided in the base-plate of the movable fish-plate, which latter apertures register with apertures formed 45 in the saddle-plate, whereby the movable fish-plate may be locked to the cross-ties by means of ordinary spikes passing through the apertures and engaging in the ties, thus dispensing with all auxiliary means for holding the 50 movable fish-plate in position.

In describing the invention in detail refer-

ence is had to the accompanying drawings, forming a part of this specification, and wherein like numerals of reference indicate like parts throughout the several views, in which— 55

Figure 1 is a top plan view of the rail-joint constructed in accordance with my invention. Fig. 2 is a transverse vertical sectional view of the chair, showing the rail in end elevation therein. Fig. 3 is a detail perspective view 60 of the chair with the rails therein, one of the latter being in cross-section.

To put my invention into practice, I provide the chair to receive and support the ends of the rails. This chair embodies a saddle-plate 1 of greater thickness along one edge 65 than along its other edge, the outer edge 2 being the thicker and being provided with suitably-placed openings 3 to receive the securing-spikes (not shown) for fastening the 70 chair along this edge to the cross-ties. On the upper face of the saddle-plate, adjacent to the outer edge thereof, is a fish-plate 4, which is cast integral with the saddle-plate, and this plate may be made so as to merely 75 extend up and engage the end of the rail, or it may be made with a vertical member which engages with the web of the rail and also underneath the tread of the rails 5. The supporting-ledge 6 of the saddle-plate, upon which 80 the rails 5 rest, is on a plane with the upper face of the thickened outer edge 2 and is consequently above the inner edge 7 of the saddle-plate. The saddle-plate is provided at 85 suitable points adjacent the inner edge with openings 3 to receive the spikes for securing the plate to the cross-ties, and upon the upper face of the saddle-plate adjacent the inner edge is an integral wedge-strip 8, the inner wall of which is inclined from one end to 90 the other and also beveled or dovetailed, as is the edge of ledge 6, whereby to receive the correspondingly-shaped edges 9 15 of the wedge-plate 10, formed integral with the base of the opposite fish-plate 11. The base of the fish-plate 11 is provided with a groove 12 in its 95 inner edge to receive the projecting portion of the base of the rail 5 which extends beyond the outer edge of the supporting-ledge 6. A part of the wedge-plate 10 therefore engages under the base of the rails, whereby to 100 insure the proper positioning of the fish-plates

with respect to each other, the movable fish-plate gripping underneath the projecting portion of the rail-bases and giving a firm support thereto.

5 In operation the rails are placed on the supporting-ledge 6, and the movable fish-plate, which carries the wedge-plate 10, is then inserted in position, the wedge-plate 10 tightening as it is moved up to position, due to the 10 inclined or tapered inner edge of the wedge-strip 8 and the making of the wedge-plate 10 of greater width at one end than at the other to conform to said wedge-strip 8. The movable fish-plate is therefore when in position locked underneath the projecting portion of the rail-base and with the dovetailed edge of the wedge-strip 8, though to securely hold the same against accidental displacement I preferably provide the wedge-plate 10 with 15 apertures 14, providing the saddle-plate 1 with registering apertures, whereby securing-spikes may be inserted therethrough into the cross-ties to securely prevent any movement of the movable fish-plate. The remainder of 20 the chair, including the saddle-plate and integral fish-plate 4, is of course firmly held by the spikes, which are inserted through apertures 3.

25 While I have herein shown and described 30 a practical embodiment of my invention, yet it will be noted that various changes may be made in the details of construction without

departing from the general spirit of the invention.

Having fully described my invention, what 35 I claim as new, and desire to secure by Letters Patent, is—

40 A rail-joint embodying a saddle-plate having an enlarged outer portion, a fish-plate formed integral with said outer enlarged portion, said portion adapted to form a seat for the rail and extending inwardly near the end of the rail-base, said saddle-plate having a reduced portion extending from the enlarged portion to the inner end of the plate, an integral wedge-shaped strip having a dovetailed edge thereto formed on the said reduced portion, said wedge-shaped strip and the enlarged portion of the saddle-plate forming a wedge-shaped groove therebetween, and 45 a movable fish-plate having a wedge-shaped portion adapted to fit in the said groove of the saddle-plate, and being provided with a recess in its face above the said wedge-shaped portion, to receive the portion of the rail extending beyond the enlarged portion of the saddle-plate, substantially as described.

50 In testimony whereof I affix my signature in the presence of two witnesses.

JAMES F. HOLLIS.
